TRAFFIC CIRCULATOR

Henry P. Compton, Abilene, Tex., assignor, by mesne assignments, to Simplex Corporation, Fort Worth, Tex., a corporation of Texas

Filed Oct. 11, 1957, Ser. No. 689,518

1 Claim. (Cl. 232—1)

The present invention relates to a traffic circulator and more particularly to a device to assist in the control of parked vehicles.

The primary object of the invention is to provide a vehicle identification device for use in conjunction with parking spaces and vehicles parking therein.

Another object of the invention is to provide a traffic circulator of the type described above which is operated by an attendant and which is locked against unauthorized operation.

A further object of the invention is to provide a traffic circulator of the class described above which is inexpensive to manufacture, simple to use and which is completely effective in obtaining an efficient circulation of traffic.

Other objects and advantages will become apparent in the following specification when considered in the light of the attached drawings, in which:

Figure 1 is a perspective view of the traffic circulator constructed in accordance with the invention.

Figure 2 is a rear elevation of the hinged side of the circulator illustrated in Figure 1.

Figure 3 is a vertical cross section taken along the line 3—3 of Figure 2 looking in the direction of the arrows.

Figure 4 is an enlarged fragmentary vertical cross section taken along the line 4—4 of Figure 2 looking in the direction of the arrows.

Referring now to the drawings in detail wherein like reference characters indicate like parts throughout the several figures, the reference number 10 indicates generally a traffic circulator constructed in accordance with the invention. The circulator 10 is secured by any suitable means (not shown) to an upright post 11 which is positioned adjacent to a parking space in a parking lot or along the street.

The parking circulator 10 comprises a rear plate 12 having a forwardly extending peripheral flange 13 integrally formed thereon. A forward edge of the flange 13 is rabbeted at 14 for reasons to be assigned. A front wall 15 is positioned forwardly of the rear wall 12 in spaced parallel relation thereto and is provided with a rearwardly extending peripheral flange 16 having the rear edge thereof rabbeted at 17 to cooperate with the rabbeted edge 14 of the flange 13 as can be seen in Figures 3 and 4. The flange 16 and the flange 13 are connected by a hinge generally indicated at 18 to permit the wall 15 to be swung downwardly and forwardly away from the wall 12 when necessary to empty the circulator 10.

A lock barrel 19 is secured to the forward wall 15 and has a latch bar 20 secured thereto for cooperative engagement with a keeper 21 formed on the flange 13 of the rear wall 12 as can be seen in Figure 3. The forward wall 15 is provided with a thickened portion 22 having a coin groove 23 formed therein and terminating in a discharge opening 24 at the lower end thereof. An outwardly bulged portion 25 is formed on

2

the front wall 15 at the upper end of the coin slot 23 and has a coin inlet opening 26 formed at the lower end thereof to permit a coin 27 to be inserted in the coin slot 23.

5 The rear wall 12 of the circulator 10 has a block 28 formed therein extending forwardly to form a rear wall for the coin slot 23.

A second lock barrel 29 is secured to the forward wall 15 and has an arm 30 fixed thereto for pivotal movement with respect to the front wall 15. The arm 30 has a pin 31 fixed to the outer end thereof and extending perpendicularly forward of the arm 30 and engageable in the coin slot 23 to support a coin 27 above the bottom thereof. A slot 32 extending generally horizontally through the coin slot 23 permits the pin 31 to be swung into the coin slot 23 on the arm 30. The block 28 on the rear wall 12 is cut out at 33 to permit the operation of the arm 30.

In the use and operation of the invention illustrated, 20 a parker parks his automobile in an empty parking space adjacent the parking circulator 10. He leaves the vehicle and returns to it upon completion of his errand. An attendant making his rounds at spaced time intervals operates the lock barrel 29 withdrawing arm 30 and pin 31 from the coin slot 23 to permit a coin 27 to drop therefrom in the event that a coin is in the slot 23. The attendant finding that there is no coin in the slot 23 uses a marking pencil and marks the last two tag numbers of the parked vehicle on a coin check 27 and drops the check through the slot 26 into the coin slot 23. On his next round, upon the completion of the allowed parking time, the attendant again operates the lock barrel 29 dropping the check 27 out of the slot 23 into his hand. He then notes the last two tag numbers 25 of the vehicle to see if the vehicle is the same vehicle previously checked into the parking space. If the vehicle is the same vehicle then an overtime parking ticket is written and placed on the vehicle in the usual manner. If it is a different vehicle, then the numbers on the check are erased and the tag numbers of the different vehicle are written thereon and the check is returned to the coin slot 23 where it remains until the next round by the attendant. The parking ticket issued by the attendant is in the form of an envelope and the traffic circulator 10 is provided with a slot 34 to receive the envelope ticket with the fine placed therein.

Having thus described the preferred embodiments of the inventions, it should be understood that numerous structural modifications and adaptations may be resorted to without departing from the scope of the appended claim.

What is claimed is:

A traffic circulator comprising a rear plate having a forwardly extending peripheral flange integral therewith, a front wall having a rearwardly extending peripheral flange integral therewith, said front wall being positioned forwardly of and in spaced parallel relation to said rear wall, a hinge connecting the lower end portions of said forwardly and rearwardly extending flanges, a first rotatable lock barrel secured to said forward wall, a latch bar secured to said barrel, a keeper for said latch bar formed on said forwardly extending flange of said rear wall, a thickened portion formed on said front wall and having a coin groove therein, said thickened portion terminating in a coin outlet at its lower end, an outwardly bulged portion formed on said front wall at the upper end of said coin groove having a coin inlet at its lower end to permit insertion of a coin into said coin groove, a block formed on said rear wall extending forwardly therefrom to form a rear wall for said coin groove, a second rotatable lock barrel secured to said forward wall, an arm fixed to said second lock

barrel for rotation therewith relative to said front wall, a pin fixed to said arm in perpendicular relation thereto and engageable in said coin groove, said thickened portion having a generally horizontal slot therein intersecting said coin groove whereby said pin may be swung into said coin groove, said block having a cut away portion for the reception of said arm.
